(57) **CLAIM**

The ornamental design for a cabin for construction equipment, as shown and described.

DESCRIPTION

FIG. 1 is a perspective view of the cabin for construction equipment according to the invention;

FIG. 2 is a front elevation view of the cabin for construction equipment of FIG. 1;

FIG. 3 is a rear elevation view of the cabin for construction equipment of FIG. 1;

FIG. 4 is a right side elevation view of the cabin for construction equipment of FIG. 1;

FIG. 5 is a left side elevation view of the cabin for construction equipment of FIG. 1;

FIG. 6 is a top plan view of the cabin for construction equipment of FIG. 1;

FIG. 7 is a bottom plan view of the cabin for construction equipment of FIG. 1; and,

FIG. 8 is a perspective view of the cabin for construction equipment of FIG. 1, showing the cabin in its construction equipment environment.

The broken line disclosure, as well as line shading in parts of the drawings are included for the purpose of illustrating use and environment and form no part of the claimed design.
